UNITED STATES PATENT OFFICE.

HARRIE D. SEVISON, OF AUBURN, INDIANA.

ELECTRICAL TIMING AND CIRCUIT-CLOSING DEVICE.

Application filed November 12, 1920. Serial No. 423,541.

To all whom it may concern:

Be it known that I, HARRIE D. SEVISON, a citizen of the United States, residing in the city of Auburn, county of De Kalb, Indiana, have invented certain new and useful Improvements in Electrical Timing and Circuit-Closing Devices, of which the following is a specification.

This invention relates to an improvement 10 in ignition systems for internal combustion engines, and more especially to an improvement in a timer designed for use in connection with such systems.

The principal object of my invention is 15 the production of a timer to be used with alternating current type of magneto or direct current system designed to effect the ignition of gas or gasoline motors with the use of battery vibrator spark coils or complicated wiring.

A further object of the invention is the provision of a device of this character to effect a positive electrical connection when the contact points are closed and only when 25 the sparks are to be produced at the spark plugs, the contact being at all other times open.

A further object of the invention is the 30 production of a device wherein friction produced between the circuit closing devices will prevent corrosion and eliminate foreign matter from the contact points, which frictional contact also prevents pitting or burning of the contact members by the flow 35 of the current when the contact is made or the circuit broken.

A further object of the invention is the 40 production of a device of the character described in which a slight rocking motion is combined with a sliding or reciprocatory movement to effect a wiping contact between the two metal members that make and break the circuit, whereby burning or 45 pitting of the surface thereof from the electrical arc is prevented.

A further object of the invention is to 50 provide a device for making and breaking an electrical circuit without the use of a condenser bridged between the two make and break members.

A further object of the invention is the 55 provision of a device of the character described in which the circuit breaker arm does not ride upon the cam but is engaged thereby only at the time of actual actua-

tion thereby, whereby wear and friction are greatly reduced.

A still further object of the invention is the provision of a device of the character described whereby the speed of the motor 60 does not affect or change the time of ignition, for the contact points are positively closed and the spark produced at the 90 degree intervals and maintained throughout the duration of the contact. 65

Other objects of the invention are mentioned and described herein.

The preferred embodiment of my invention is illustrated in the accompanying drawing in which Figure 1 is a side elevation showing a portion of the device broken away and in section; Fig. 2 is a plan view of the open face of the improved timer for a four cylinder internal combustion engine; Fig. 3 is a view showing one of the make 70 and break members and the position of the cam member when the make and break member is initially affected thereby; Fig. 4 is a view showing the same members in different positions; Fig. 5 is a fragment showing a section on the line 5—5 of Fig. 2; Fig. 6 is an end view of the frame of one of the make and break members; Fig. 7 is a view of one of the contact arms; and Fig. 8 is 75 an end view of the same member. 80

Similar numerals of reference indicate like parts throughout the several views on the drawing.

Referring to the drawing in detail, the 85 numeral 1 indicates the timer casing into which the rotary cam shaft 2 projects, upon which shaft the cam 3 is rigidly secured, the latter being adapted to effect actuation of the make and break members, as hereinafter described. The cam 3 is provided with the 90 embossment 4 which may give a general elliptical configuration to the cam. 95

In the accompanying illustration a timer or controller for a four cylinder internal combustion engine is shown and in which are mounted four separate and distinct make and break members or systems which are arranged around the cam 3 and spaced equidistant from each other each of which is a replica of the others. The numerals 5, 100 6, 7 and 8 indicate the four make and break members each of which is mounted for oscillation within the casing 1, as herein-after described, one only of which will be described. The numerals 9, 9 indicate a plu- 105 110

rality of contacts arranged at intervals interiorly of the casing 1, each of said contacts being rigidly secured to the inner leg of a U or channel shaped electrode bracket 10, the opposite leg of said bracket being carried upon the headed end of the terminal stud 11. An insulating washer 12 is interposed between each bracket 10 and the interior of the casing 1, and an insulating plug 10 or bushing 13, penetrated by the stud 11, insulates the latter from said casing. A pair of lock nuts 14 and 15 may be threaded upon the outer end of each terminal stud 11. As shown, there is a substantial space 15 between each contact 9 and the headed inner end of the stud 11 which serves as the mount for the bracket 10, which space is material for the purpose hereinafter described.

As stated, the make and break units 5, 20 6, 7 and 8 are alike in construction, each of which comprises a carrier bracket 16, a contact arm bracket 17, a fiber block 18, and springs 19 and 20, the entire unit being pivotally mounted upon a stud 21 rigidly secured in the end wall of the casing 1. Each carrier bracket 16 comprises side walls 22 and 23 which are rigidly aligned and connected by a web or transverse wall 24, the fiber block 18 being rigidly fastened between 30 the side walls thereof by pins 25, 25, the opposite end of each of said bracket side walls being suitably apertured at 26 to receive the stud 21.

Projecting laterally from one end of the bracket wall 23 adjacent the block 18 is a lug or stop arm 27 adapted to project into the recess 28 formed in the end wall of the casing 1 and which is adapted to be pressed into engagement with one wall of said recess 40 by the spring 19 to limit the inward swing of said bracket, as hereinafter described.

The contact arm bracket 17 may comprise the web portion 29, the two spaced side walls 30, 30 projecting angularly therefrom, the contact arm 31 extending angularly from the web 29, and the contact member 32 rigidly secured to the arm 31, said contact member being adapted to cooperate with the contact 9 on the bracket 10. The walls 30, 50 30 of the bracket 17 are suitably apertured at 33, in registration, to pivotally mount said bracket upon the pivot pin 34 between the walls 22 and 23 of the bracket 16, said pin 34 having its opposite ends secured in said walls. The bracket 17 is provided also with the aligned apertures 35, 35 formed in the two walls 30, 30, said apertures being engaged by the stud 21, which apertures are greater in diameter or size than said stud 60 to enable an oscillatory or rocking movement of the bracket 17 on the pivot pin 34.

The spring 20 may be coiled around the pivot pin 34 and has one leg thereof bearing against the end of the web 24 of the bracket 16, the other leg of said spring bear-

ing against the inner periphery of the web 29 of the bracket 17, whereby the bracket 17 is normally pressed inward toward the shaft 2, and whereby the stud 21 is caused to engage the side of the bracket aperture 35 70 most remote from the bracket web 29, as illustrated in Fig. 7 of the drawing.

The bracket spring 19 is coiled around the stud 21 and has one leg thereof engaging the inner periphery or circular face of the casing 1 and against which it bears, the other leg of said spring engaging and bearing against the pin 34, whereby the fiber block 18 of each unit 5, 6, 7 and 8 is normally pressed inward toward the cam 3, which inward movement is limited by the engagement of the stop arm 27 with the wall of the recess 28, as described, thereby normally holding the block 18 spaced from the circular body portion of the cam 3. The inward oscillatory movement of the unit 5, 85 as described, swings the contact arm 31 outwardly toward the head of the terminal pin 11, whereby a disengagement of the contact points 9 and 32 is effected. Each block 18 90 may have the beveled or sloping faces 36 and 37 to effect functions hereinafter described.

In operation, the cam boss 4 first engages the inclination 36 of a block 18, then the flat face thereof, and thereafter the inclination 37 of said block, thereby effecting an oscillatory movement of the entire unit 5 during which movement the contact arm 31 is first swung inwardly (see Fig. 3) and thereafter a reciprocatory movement thereof is effected. The reciprocatory movement of the contact arm 31 of the bracket 17 is made possible by the pivotal action of the latter, said pivotal action being limited by the stud 21 which engages alternately on opposite sides of the aperture 35, first, normally by spring action, as described, and thereafter by the action of the cam boss 4 on the block 18. 105

The effect of the oscillation and reciprocatory movement of the contact arm 31 is as follows: First, the contact points 9 and 32 are brought into engagement; second, the contact 32 is drawn across the face of the contact 9 to a point as indicated in Fig. 4 with the members positioned as shown; third, as the inclined face of the block 18 slides inwardly upon the edge of the cam boss 4, the contact 32 slides back to the position indicated in Fig. 3; and fourth, as the cam boss 4 departs from the block inclination 37, the action of the spring 19 restores the unit 5 to its normal position, in which the stop lug 27 again engages the wall of the recess 25, and in which position the contact 32 is poised intermediate the head of the terminal stud 11 and the contact 9. 115

The body of the cam 3 being normally out of engagement with the blocks 18 has a tendency to and does actually off-set any inac- 120 125 130

curate workmanship which commonly occurs in the manufacture of devices of this character. This is to say, if the cam shaft 2 is not central with the outer periphery of 5 the flange of the casing 1, the make and break members 5, 6, 7 and 8 will not be operated eccentrically as the cam boss 4 is actuated. This greatly prolongs the life of the make and break members, and therefore 10 fore the entire timer mechanism. While this device is particularly desirable for use in ignition systems for internal combustion engines, its use is not confined to this device, for it can be used successfully in any 15 electric appliance wherein the circuit is made and broken with or without the aid of a condenser.

While a perfect embodiment of the invention is illustrated in the accompanying drawing, it will be appreciated that the invention is not limited to the exact construction shown and described, for many changes and alterations may be made therein without departing from the spirit of the 25 invention.

I claim:

1. The combination with a casing, a plurality of contact members carried thereby, and a rotative embossed cam element, of a 30 plurality of oscillatory spring pressed members mounted within the casing and adapted to coact and to be outwardly actuated by said cam element; a spring pressed contact arm pivotally mounted upon each oscillatory member and projecting therefrom into proximity with one of said contact members to make and break a circuit, said contact arm being adapted to be swung simultaneously 35 with the actuation of said oscillatory member by said cam element, whereby said contact arm is first swung into yieldable engagement with one of said casing contact members and thereafter moved across the face thereof to effect a wiping contact therewith; 40 and stop means adapted to be engaged by

said spring pressed contact arm when the latter is disengaged from said casing contact member.

2. The combination with a casing and a rotative embossed cam element, of a plurality of oscillatory elements adapted to coact with said cam element and to be outwardly actuated thereby; a yieldable contact arm carried by and projecting from each of said oscillatory elements to make 50 and break a circuit, said contact arm being adapted to swing toward the center of said casing when said oscillatory element is outwardly actuated by said cam; and a contact to coact with each of said contact arms, said contact being arranged intermediate the contact arm and said cam element and adapted to be engaged by said contact arm upon the outward actuation of said oscillatory element. 55

3. The combination with a casing and a rotative embossed cam element, of a plurality of oscillatory elements arranged around said cam element and adapted to coact therewith, said elements being spring 60 pressed toward said cam element; a yieldable contact arm carried by and projecting angularly from each of said oscillatory elements to make and break a circuit, said contact arm being adapted to swing inwardly 65 of said casing when said oscillatory element is outwardly actuated by said cam; and a contact to coact with each of said contact arms, said contact being arranged intermediate the contact arm and said cam element and adapted to be engaged by said contact arm upon the outward actuation of said oscillatory element, whereby, upon causing a full oscillation of said oscillatory element, 70 said contact arm is caused to engage said contact and to effect a reciprocatory movement upon the face thereof. 75

In testimony whereof I hereunto affix my signature this 4th day of November, 1920.

HARRIE D. SEVISON.
